US0D1040784S

(12) **United States Design Patent** (10) **Patent No.:** **US D1,040,784 S**
(45) **Date of Patent:** **** Sep. 3, 2024**

(54) **WIRELESS EARPHONES WITH CHARGING CASE**

(71) Applicant: **Besing Technology (Shenzhen) Co., Ltd.**, Shenzhen (CN)

(72) Inventor: **Wenfeng Deng**, Shenzhen (CN)

(73) Assignee: **Besing Technology (Shenzhen) Co., Ltd.**, Shenzhen (CN)

(**) Term: **15 Years**

(21) Appl. No.: **29/871,691**

(22) Filed: **Feb. 24, 2023**

(51) LOC (14) Cl. **14-01**

(52) U.S. Cl.

USPC **D14/223**; D13/108

(57) **CLAIM**

The ornamental design for a wireless earphones with charging case, as shown and described.

DESCRIPTION

FIG. 1 is a top perspective view of wireless earphones with charging case, showing my new design, the wireless earphones are shown separately for ease of illustration;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of the charging case of the wireless earphones with charging case, shown separately for ease of illustration;

FIG. 10 is a bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a front perspective view thereof, in an open position; and,

FIG. 18 is a front perspective view of a case of a wireless earphones with charging case thereof, in a closed position thereof.

The broken lines in the drawings illustrate the portions of the wireless earphones with charging case, which form no part of the claimed design.
